Primary Examiner — Freda S Nunn(74) *Attorney, Agent, or Firm* — F. Chau & Associates, LLC(57) **CLAIM**

The ornamental design for a network equipment rack, as shown and described.

DESCRIPTION

FIG. 1 is a front perspective view of a network equipment rack showing our new design;

FIG. 2 is a rear perspective view thereof;

FIG. 3 is a top plan view thereof;

FIG. 4 is a bottom plan view thereof;

FIG. 5 is a right side view thereof; and,

FIG. 6 is a front view thereof.

The left side view of the network equipment rack is a mirror image of the right side view thereof.
